ELECTRIC FLOOR MACHINE

William L. McGee, Media Borough, Pa.

Application February 6, 1929. Serial No. 337,783

6 Claims. (Cl. 91—44)

One of the objects of my invention is to provide a machine of the type above referred to, which is light in weight, attractive in appearance, easily manipulated, having its operative parts 5 well covered and protected, and having smooth, rounded exterior surfaces, all particularly adapting the device for household use.

A further object of my invention is to make a floor machine which may be used for various purposes as, for example, to polish a floor that is already waxed and does not require the application of more wax in order to re-polish the same; to enable a housewife to removably secure to the floor polishing machine an appliance which will 15 deliver to the floor, in advance of the brushes, the proper amount of wax to be spread and polished by the brushes, said appliance containing a mechanically operated pump for delivering the wax from a reservoir to the floor, said pump being 20 a rotary one operated by rollers on which the weight of the appliance is supported on the floor, whereby the amount of wax delivered from the machine or appliance to the floor, when adjusted, is always the same for a given area of the floor. 25 A further object of my invention is to actuate a mechanical feeding mechanism of a waxing appliance by the to and fro movement which is ordinarily used in polishing and finishing floors, and operative to deliver a given amount of wax 30 for any given area of the floor, irrespective of the speed at which the device is moved over the floor.

A further object of my invention is to provide a waxing appliance for a floor polishing machine wherein the wax is delivered in advance of the 35 brushes whenever the brushes are moved bodily in one direction as, for instance, forwardly, and to automatically stop the delivery of wax to the floor whenever the movement of the device in the opposite direction, as for instance, rearwardly.

40 A further object of this invention is to provide a device for attaching the brushes to the spindles by which they are carried and rotated, which is very simple in construction and easily operated and without mechanical complications, so that 45 it is merely necessary in order to remove a brush, for one to pull it straight off the end of the shaft and against slight resistance, and in order to attach a brush to the shaft, for one to simply slip or slide the brush on over the lower end of the 50 shaft, the brushes being capable of being interchangeably attached to either of the two brush shafts with which the machine is provided.

A further object of my invention is to enable 55 the housewife to easily remove one set of brushes and replace them with another similar set of

brushes or tools, dependent upon the use to which she wishes to put the machine, all said tools being easily attached to either spindle irrespective of the direction in which the spindle is rotated by the driving motor. 60

A further object is to provide a device comprising a pair of floor polishing brushes with an appliance for containing and delivering wax to the floor, which for its operation imposes no additional work upon the electric motor by which 65 the brushes are rotated, said waxing appliance being detachably connected to the housing of the brushes and its weight being supported on the floor by one or more rollers which, by their rotation in traveling over the floor, operate a 70 mechanism for positively delivering wax to the floor.

A further object of my invention is to practically prevent any one who is not mechanically competent from changing the adjustments of 75 the thrust bearings of the relatively high speed electric motor by means of which the polishing brushes are rotated in opposite directions.

A further object of my invention is to provide a telescoping connection between the ends of the 80 shafts and the brushes connected thereto and to dispense with any screw threaded connection, whereby the brushes may be easily slipped on over the ends of either of the shafts are removably locked thereon in driving engagement therewith. 85

A further object of my invention is to provide the telescoping parts of the brush shafts and brush sockets with a locking device comprising a member in one part, spring pressed toward the 90 other part and seated in a transverse groove of the said other part when the brush and shaft are in locked engagement with each other.

A further object of my invention is to provide the groove in one of said parts, as above described, 95 with a rounded edge over which the rounded end of the plunger may be readily slid in removing the brush from the shaft, and by which the depression of the plunger against the tension of the spring is facilitated. 100

Further objects of my invention will appear in the specification and claims below.

Referring now to the drawings forming a part of this specification and in which the same reference characters are used throughout the various 105 views to designate the same parts.

Fig. 1 is a top plan view of the housing or casing of my floor finishing machine, with the waxing appliance and with the handle removed, and also with one of the cover plates, forming 110

a closure for the chamber in which the gearing is mounted, removed to expose the worm gear and the jam screw for locking the thrust bearing for the motor shaft.

5 Fig. 2 is a front elevational view of the casing of the floor polishing machine shown in Fig. 1 with the yoke of the handle shown in dot-and-dash lines and with the waxing appliance omitted but showing the holes or openings within which 10 the studs of the wax appliance may be inserted and locked and supported.

Fig. 3 is a plan view, similar to Fig. 1, but with the left-hand half of the mechanism in horizontal cross-section in a plane coincident with the axis 15 of the motor shaft and showing the waxing appliance mounted on the front side of the housing.

Fig. 4 is a vertical cross-sectional view of the apparatus on the line 4—4 of Fig. 3.

Fig. 5 is an enlarged sectional view showing in 20 detail the thrust bearing for the motor shaft, and the lock therefor.

Fig. 6 is an enlarged sectional view of a portion 25 of a brush shaft and socket sleeve, the unitary locking member, the locking plunger thereof and shape of the upper wall of the groove rounded to facilitate the removal of the brush.

Fig. 7 is a horizontal sectional view on the line 7—7 of Fig. 5.

Fig. 7^a is a fragmentary vertical axial sectional 30 view of a slightly modified construction.

Fig. 8 is a vertical sectional view on the axis of the right-hand brush spindle of Fig. 1.

Fig. 9 is an end elevational view showing the 35 waxing appliance mounted on the front of the housing.

Fig. 10 is an elevational view on a larger scale, of the fastener for detachably securing the waxing appliance to the housing.

Fig. 11 is a view of the waxing appliance and 40 mechanism on a larger scale than that of Figs. 3 and 9, the lower part being in vertical cross-section on the line 11—11 of Fig. 12 to show the rotary pump for positively mechanically feeding wax from the reservoir to the floor and the valve for regulating and controlling the flow of wax 45 to the floor.

Fig. 12 is a front elevational view of the waxing appliance; and

Fig. 13 is a horizontal cross-sectional view on 50 the line 13—13 of Fig. 12, but on a larger scale.

My floor finishing machine comprises a casing or housing 1, preferably composed of two parts, 2 and 3, provided with a telescoped joint 4 offset a little from the median line of the machine, the 55 two parts being rigidly secured together in any suitable manner as by two screws 5, 5 passing through the vertical wall of the part 2 and fitting into suitable lugs or projections 6, 6 in the part 3 as indicated in Fig. 3. The casing or housing 60 1 is provided with an enlarged chamber 7 in which are the rotor 8 and stationary field windings 9, 9 of the electric motor 10 and on each side of the enlarged chamber 7 are two cylindrical chambers 11, 11, the axes of which are vertical 65 and parallel to each other, and offset to the front of the axis of the motor shaft 12. The casing or housing 1 supports the bearings for the motor shaft 12, the bearings being preferably tubes 13, 13, of any suitable material, cut away 70 on one side adjacent the vertical chambers 11, 11, to permit the worm gears 14, 14' mounted on the upper ends of the brush shafts 15, 15 respectively to mesh with right and left hand worms 16, 16' with which said motor shaft 12 is 75 provided and through which the motion of the

motor shaft 12 is imparted to the brush shafts 15 to drive them in opposite directions. Each end of the motor shaft 12 is preferably provided with a conical recess 17 into which fits a hardened ball 18, said ball being engaged on the opposite side by a projection 19 on the end of a short screw 20 threaded into the casing in alignment with the axis of the motor shaft 12. The surface of said projection 19 adjacent the ball 18 is preferably plane and normal to the axis of the shaft 12 and said ball and projection are preferably of hardened steel.

The surfaces 21 of the casing or housing 1 surrounding the upper end of the vertical cylindrical chambers 11, 11 are preferably flat and horizontal and downwardly from these flat surfaces

21 in a vertical plane coincident with the axis of the motor shaft is driven a jam screw 22, the lower end of which may be forced into the screw-

threads of the screw 20 to lock the screw 20 from rotation when once the proper adjustment of

the bearing surface of the projection 19 against the ball 18 has been effected. In this locking

position the upper end of the jam screw is at least flush with and is preferably below the plane 100 of the surface 21, and I provide the upper ends

of the screws 22 with an axial socket 22', polygonal in transverse cross-section, thus requiring

a special wrench for the screws 22. The casing or housing 1 is preferably provided with two 105 covers 23 each respectively fitting over the flat

surfaces 21 and covering the same and forming a closure for the upper ends of said cylindrical chambers 11, said covers 23 being preferably per-

manently retained in place by screws 24.

It will thus be seen that once the thrust bear-

ings of the motor have been adjusted and the plates 23 secured in position, it will be im-

possible to turn said screws 20 until after the jam screws 22 have been loosened. Since 115

the location of the jam screws 22 and in fact their very existence, is concealed by the

cover plates 23, one unfamiliar with the inner

construction of the machine does not know how to release the screws 20 to adjust the bearings 120

and, if he does remove the plates or covers 23, he

will probably not have a wrench which will fit the

socket 22'. In this way an attempted adjustment

of the bearings by an inexperienced person, or a

person who is not mechanically inclined, is prac-

tically prevented and this insures against the un-

necessary tampering with the thrust bearings,

and the consequent mis-adjustment of the same,

and insures the proper operation of the mecha-

nism over long periods of time.

Each worm gear 14 is preferably keyed to the

upper end of a brush shaft 15 by a key 25 and is

permanently retained thereon by a nut 26. Each

brush shaft 15, 15 is preferably mounted to turn

in a pair of spaced bearings 27, 27, forced into

135 and permanently frictionally retained in the

lower portion of a cylindrical chamber 11. The

space between the two aligned bearings 27, 27,

constitutes a chamber in which I preferably fit

absorbent material, such as felt washers 27' to re-

tain any lubricant which might work into the

chamber, and thus prevent it from leaking

through the lower bearing 27 to the floor.

Below its lower bearing 27 each shaft 15 is

preferably provided with a flange 15' providing

145 a shoulder, and below said flange 15' with a brush

engaging end 28 which is preferably polygonal in

transverse cross-section. I preferably make

these ends 28 substantially square in transverse

cross-section and the vertical corners between

80

150

the flat surfaces 28' rounded. This squared end 28 is adapted to slide easily longitudinally into a similarly shaped socket hole 29 in a socket bushing 30 attached to the upper side of a circular brush 31, as by screws 32 passing through the flange 30'. This socket bushing 30 preferably fits into a hole passing through the back 33 of the brush vertically at the center thereof and the lower end of the socket bushing 30 is provided with a rigid loop 34 approximately semicircular in shape, extending downwardly into a conical recess 35 on the under side of the back 33 of the brush so that an operator may invert the housing, insert a finger through the loop 34 and easily draw the brush 31 off from the squared end 28 of the shaft by exerting a jerk on the loop. The brush 31 is provided with a plurality of rows of bunches of bristles 36, by which the weight of the entire mechanism is supported upon the floor.

One of the surfaces of the interlocking portions of the shaft 15, and the socket sleeve 30 as, for instance, a surface 28' of the shaft, is provided with a plunger 37 which is spring pressed toward a coating surface 29' in the interlocking portion of the bushing 30. I preferably use a locking device which is a unit 38 comprising the plunger 37 having a preferably spherical outer end housed in and normally held projecting well beyond the otherwise open end of a cartridge shaped shell 39 by a spring 40, surrounding a rearwardly extending rod 37' unitary with the plunger 37 and projecting through a small opening in the closed end 41 of the shell 39. Said rod 37' is provided with a head 42 outside the closure 41 to restrain the outward or forward movement of the plunger 37 beyond a predetermined point. And this device is preferably inserted into a hole 43 drilled into the squared end 28 of the shaft 15 deeper than the over-all dimension of the plunger 37, rod 37', and head 42 by at least the amount that the plunger 37 is to be depressed.

The surfaces of the other coating portions of the shaft and sleeve, and preferably the surfaces 29' of the holes 29, are provided with grooves 44, one on each surface 29'. When, therefore, a brush is slipped over the squared end 28 of the shaft 15 and pressed toward the collar 15', the plunger head 37 will first be engaged by the tapering surface 45' at the upper end of the hole 29 and will be depressed into the shell 39 and sliding over the shoulder 45 will slide down over the reversely curved or tapered surface 44' to the deepest part of the groove 44 in which position the upper end of the bushing 30 will be seated on the flange 15'.

The pressure of the springs 40 on the plungers 38 when the latter are thus seated in the recesses or grooves 44, as shown in Fig. 6, is made amply sufficient to retain the brushes securely on the ends of the shafts 15 whenever the device, as a whole, is lifted from the floor. In order, however, that there may be no difficulty in removing the brushes from the shafts 15, I preferably make the upper wall 44' in the form of a reversed curve longitudinally so that it will have a camming action on the spherical end of the plunger 37 and easily depress the plunger 37 into its shell 39 against the tension of the spring 40 by the application of a sharp tug or pull on the loop 34 of the socket sleeve 30. With the four walls or surfaces 29' of the socket hole 29 thus provided with undercut grooves 44 in the manner above described, no care is required to be exercised in placing the brushes on the ends of the shafts. As soon as the brush is

turned to bring a flat side 29' of the hole 29 against a flat surface 28' of the end of the brush shafts, the brush may be easily slipped over the end 28 of the brush shaft into locking position and the plunger will project into the groove 44 with which the wall adjacent thereto is provided. Heretofore it has been deemed necessary to provide the ends of the brush shafts with right and left-hand screws and, of course, that precludes any interchange of brushes from the right to the left-hand side of the machine and vice-versa and requires the operator to know which way a brush must be rotated to take it off or put it onto the shaft. By my improvement, such difficulties are avoided. Any of the brushes which can be used in my device, can be merely slipped over the end of either shaft which fits into a similar polygonal hole in the brush, and to remove the brush one merely applies a sharp tug or jerk to the bail at the middle of the brush and the brush slides off the end of the shaft. This construction forms the subject-matter of my U. S. Letters Patent No. 1,865,032, granted June 28, 1932, the application of which was filed as a division of the present specification.

Within the enlarged chamber 9 and rigid with the motor shaft 12, I preferably provide a fan 46 and the ends of the enlarged chamber are preferably provided with passages 47, 48. Air may be drawn through the passages 47 by the fan, may be impelled over the windings of the motor and delivered out through the passage 48, thus keeping the motor cool under working conditions.

The casing 1 is also preferably provided with a yoke 49 which is pivotally secured to the opposite sides of the casing at the ends of the yoke by screws 50 and in the casing adjacent the pivot screws 50 I preferably provide spring pressed plungers 51 similar to those employed at the polygonal end of the brush shafts and adapted to engage a slight depression 52 in the head of studs 53 each carried by an arm respectively of the yoke and in registration or alinement with the plungers 51 when the yoke is in substantially vertical position, to hold the handle vertical when the device is not in use. At the upper point of the yoke 49 and on the underside thereof, I provide a recess in which is fitted an electrical receptacle 54 for the insertion of the prongs of an electric plug 55 attached to the end of a short cable 56 which passes through an opening 57 in the rear wall of the casing and by means of which electric power may be communicated to the motor.

The receptacle 54 is connected by a long cable 58 passing through the recess upwardly through the hollow shaft or handle 59 and through the grip 60 out of the end of the grip and is of a length sufficient to permit of its attachment to a suitable electric receptacle in a baseboard or otherwise provided as is common to the use of vacuum cleaners and like domestic apparatuses.

The electric switch 61 which I mount in the grip 60 has a trigger-like operating lever 62 which is yieldingly held pressed forwardly by a spring 63. In this position the circuit is broken. When the operator grasps the grip 60 and draws back on lever 62 as on a trigger, such movement of the trigger operates the switch 61 to close the circuit. I have not undertaken to illustrate the switch mechanism 61, except diagrammatically, but I have shown the operating finger or trigger 62 as normally held pressed forwardly or downwardly by a spring 63.

I have indicated the position of the outer ends of the commutator brushes 64 or the holders for the same, on diametrically opposite sides of the commutator 65, but they may be of usual and standard construction. I also preferably encircle the lower edge of the skirt 1' of the housing or casing 1 with a rubber cushion 66 to prevent the marring of the walls or furniture which may be struck by the apparatus in operating it.

10 Since my apparatus is to be used at times as a wax applying mechanism, I preferably mount on the inside lower forward edge of the skirt 1', at the middle of the casing, on a lug 67 therein provided, a plate 68 on the inner side of which are rigidly secured two fasteners 69, 69 respectively in axial alignment with two holes 70, 70 through the plate 68, the lug 67 and the skirt 1', the axes of the holes being preferably parallel and horizontal.

20 The fasteners 69 are what are commonly used to removably secure the side curtains of an automobile, each comprising a casing or housing 71 within which are secured two lengths or stretches 72, 72 of resilient wire oppositely bowed slightly away from each other where they cross or traverse an otherwise clear opening 73 through the housing 71. Said lengths of spring wire are forced apart when the conical head of a pin is inserted through the housing 71 between them, and they spring back toward each other into a groove or neck with which the pin is provided immediately to the rear of the conical end thereof as soon as the said groove comes into registration therewith. Two of such fasteners 69 mounted on the base or carrier plate 68 are sufficiently illustrated in Fig. 9 to indicate the kind or type of fastening means with which I prefer to provide the casing or housing 1.

40 In Fig. 7^a the lower end 28^a of the shaft 15 is cylindrical and fits into a cylindrical hole 29^a in the bushing 30^a. The end 28^a is provided with a cross-pin 28^b, the projecting ends of which fit into notches 30^b in the top edge of the bushing 30^a. The inner surface of the hole 29^a is provided with an annular circumferential groove 44^a and the tapering surface 45^a at the upper end of the hole 29^a, and the curved wall 44^a, all to coact with a spring pressed plunger 37, as above described in connection with Figs. 1 to 7.

50 I have also shown the loop or bail 34^a as separate from the sleeve 30^a, having its ends fitting against the wall of the conical recess 35 and secured in place by screws 32^a passing through the ends of the loop 34^a and the back 31, and threaded into the flange 30^a. I preferably upset the upper ends of the screws 32^a to prevent loosening. There are certain advantages to this construction. The brushes are perhaps more easily slipped over a cylindrical end of a brush shaft than over a polygonal end; and no obstruction such as an integral loop or bail 34 is present to interfere with free access to the interior of the hole 29^a from either end of the bushing 30^a thereby facilitating the mechanical operation of the hole to fit the shaft. The operation is precisely the same as above described in that the brushes may be slipped over the lower end of either shaft irrespective of its direction of rotation and into driving engagement therewith, and are easily removed by pulling on the loop.

55 My waxing appliance, illustrated in detail in Figs. 11, 12, and 13, comprises a generally cylindrical wax container or reservoir 74 having a cylindrical neck 75 at its lower end and a cover

or closure 76 at its upper end. The neck 75 is tightly permanently fitted into a cylindrical chamber 77 in the upper part 78' of the carriage body 78. The lower part 78'' of the carriage 78 constitutes a housing within which is mounted two small spur gears 79, 80 having small intermeshing teeth. The lower part 78'' of the carriage body is preferably provided with a generally oblong recess 81 of a depth equal to the thickness of the gears 79 and 80, and the ends of the recess are arcuate and smoothly fit around and against preferably more than one-half of the outer periphery of the gears 79 and 80. The carriage 78, includes a flat cover plate 82 smoothly bearing against the sides of the gears 79 and 80 which lie flat against the bottom surface of said recess 81. The plate 82 is preferably held in place by screws 83.

60 The forward gear 79 is rigidly keyed to a shaft 84 mounted to rotate in alined bearings 85, 85 in the carriage and plate 82 respectively. On the ends of the shaft 84 are the wheels 86, 86 of the carriage, rigidly secured to the shaft in any suitable manner, as by the pins 87. The wheels 86 are preferably provided with rubber tires 88 to provide sufficient friction to insure their rotation on the polished floor.

65 I preferably provide the carriage 78 with glands or stuffing boxes 89 just outside of the bearings 85 to prevent wax from leaking through said bearings.

70 Since the wall of the recess 81 is preferably in contact with a substantial portion of the perimeter of the gear 80, the said gear 80 may be freely rotated by the gear 79 intermeshing therewith, without providing said gear 80 with a shaft or pivotal journal. Just above the intermeshing portions of the teeth of the gears 79 and 80, I provide a small chamber 90 which communicates, by a passage 91, with a chamber 77 and so with the interior of the reservoir or wax container 74. Below the intermeshing portions of the teeth of the said gears, I provide a similar small chamber 92 which in turn communicates with a passage 93 extending vertically downward and preferably terminating in a slightly larger bore into which is fixedly secured in any suitable manner a thin walled tube 94 having an oblique end 94' the lowest portion of said oblique end being rearmost of the carriage. I also preferably provide the carriage with a valve 95 for regulating and controlling the delivery of wax through the passage 93, and for closing the passage, the same preferably consisting of a screw 96 screwthreaded into a hole 97 which passes transversely through the axis of the passage 93. The diameter of the screw is preferably a little greater than the diameter of the passage 93. The outer end of the screw 96 is preferably provided with a knurled head 98 by means of which the screw may be rotated. The opening or hole 97 is preferably so deep that when the screw has been advanced to the bottom of the hole 97, the said screw will extend across and close the passage 93.

75 From the rear side of the carriage extending rearwardly from the upper part of the carriage is a lug 99 and depending therefrom are preferably two vertical parallel cylindrical studs or pins 100, 100 which are of a diameter to loosely fit and slide through parallel vertical holes 101 alined therewith and in a cross bar 102. This cross bar is preferably retained on the pins or studs 100 by cross pins 103. Extending rearwardly from the cross bar 102 are two generally cylindrical studs 104 parallel to each other and horizontally dis-

posed and terminating in conical ends or heads 105, the studs 104 being provided each with a circumferential groove 106 forming a neck between the head and the cylindrical body of the 5 stud. The wall 106' of the groove 106 which is nearest the head 105 is preferably a conical surface tapering rearwardly outwardly from the bottom of the groove to the head.

These studs 104 are rigidly mounted in the cross 10 bar 102 and are adapted to be brought into alignment with and inserted into the holes 70 in the skirt 1' of the casing or housing 1 and through the fasteners 69 to a point where the wires 72 of the fasteners are seated or rest in the grooves 15 106 immediately adjacent the conical heads 105. To operatively secure my waxing appliance to the front of the housing for the polishing brushes, one merely has to insert the stud 104 into the holes 70 and to remove one merely has to pull the 20 carriage and with it the studs away from the housing 1, drawing the studs out of their locking engagement with the fasteners 69. The slanting wall 106' of the grooves are operative to force the wires 72 apart by firmly pulling the waxing 25 appliance away from the housing.

When attached to the housing, as shown in Fig. 9, substantially the entire weight of the waxing appliance and the wax carried thereby, is supported upon the wheels 86 for the vertical 30 studs 100 slide freely through the openings 101 in the cross bar 102 and permit the waxing appliance to rise and fall with respect to the housing 1 as the waxing appliance travels over the floor.

35 In practice, the upper ends of the chambers 11 are filled with a grease in which the worms 16, 16' and worm gears 14, 14' rotate and to prevent this grease from being forced through the bearings of the rotor shaft 12 toward the rotor 8, I 40 make the pitch of the worms 16, 16' such as to cause the grease with which the worms are surrounded to move in a direction away from the rotor. Thus assuming the top of the rotor to rotate forwardly, in a clockwise direction looking 45 toward the rotor from the left hand side of Fig. 3, as indicated by the arrow placed on the rotor in said figure, then the pitch of the worm 16 shown in Fig. 3 will be a right-hand pitch and the grease in the chamber 11 will be churned in 50 the direction that the worm gear 14 rotates, as indicated by the arrow on the worm gear 14 in Fig. 3, and the movement of the grease in the chamber 11 adjacent the worm will be away from that part of the bearing of the shaft 13 between 55 the worm 16 and the rotor 8 and thus away from said rotor. In like manner, the worm 16' on the other end of the shaft, and as shown in Figs. 1 and 4, is provided with a left-hand pitch so that the grease in the chamber 11 around the worm 16' 60 will similarly move or be forced or crowded by the worm in a direction away from the rotor, as indicated by the arrows on the worm gear 14' in Figs. 1 and 3.

65 I preferably fit a washer 107 in a recess in the casing 1 at the inner ends of the bearing tubes 13, tightly fitting the shaft 12 to insure that no grease from the chamber 11 shall leak past the bearings 13 to the commutator 65 or to the fan 70 46 of the rotor 8.

The vertical brush shafts 15 are preferably in front of the horizontal motor shaft 12 and the brushes 31 will consequently be rotated in opposite directions, the perimeters of the brushes, 75 at the front of the casing or housing, 1, rotating

toward each other and toward the middle line of the casing.

When the appliance is in use, the forward motion of the floor polishing machine and the consequent rolling of the wheels on the floor, 80 will produce a rotation of the shaft 84 and gear 79 in the direction of the arrow (Fig. 11) and a consequent rotation of the intermeshing gear 80

in the opposite direction away from the chamber 90. When, therefore, the passage 91 and chamber 90 are filled with a fluid wax, the gears 80

constitute a rotary pump which pumps the wax from the reservoir 74 and delivers substantially metered quantities of wax to the floor, the quantity 85 depending on the extent of the forward movement of the machine.

The spaces between adjacent teeth of each gear and the arcuate walls of the recess 81 are filled with wax, and it is expressed into the chamber 96 from between the gear teeth, as the said teeth come into mesh 90 above the chamber 96, thereby filling the chamber 92 and forcing the wax downwardly through the passage 93 and tube 94 to the floor in advance 95 of the brushes and in controlled predetermined quantities.

When the floor finishing machine is 100 moved backwardly or in the opposite direction, then the gears revolve in the opposite direction and there is no delivery of wax to the floor during such movement.

The amount of wax delivered to the floor is controlled by and is proportional to the distance that the apparatus is advanced in a forward direction, a certain amount being delivered in a given travel or distance and that this amount is not varied by the speed at

which the apparatus is moved backward and forwardly. The delivery of wax is absolutely independent of the motor which is used to impart 105 rotary movement to the brushes. When the floor does not require waxing but merely a repolishing, the waxing appliance is easily removed with-

110 disturbing or disarranging any part of the brush operating mechanism and different brushes, if desired, may be easily substituted for those which were used in applying the wax.

115 While my waxing appliance is particularly adapted for the use of a wax which is fluid or liquid at ordinary household temperatures, the relatively small, easily removed and attached waxing unit, makes possible the use of normally solid wax in a melted condition, it being only 120

necessary to heat the waxing unit in any suitable manner and to fill it with melted wax which will 125 ordinarily remain fluid for an hour or two, which is sufficiently long to enable one to wax and polish the floors before it solidifies. If the wax should 130

solidify during such use, the reservoir may be readily detached, re-heated and reattached to the casing.

135 Similarly, if any normally liquid wax standing in the unit should solidify because of exposure to temperatures below those at which the wax is liquid, or because of the evaporation of the solvent or vehicle, it is only necessary to remove the unit, heat it and in this manner bring the wax back to a fluid condition.

140 The positively acting mechanical feed is also important in this connection for, once adjusted, the same amount of wax is delivered to the floor, irrespective of the density of the fluid. Many liquid waxes contain clots, particularly if the wax

145 has not been thoroughly agitated before using. Such clots stop or vary the gravitational flow of wax through a small tube like the passage 91. But the pumping action of the gears 79, 80 prevents such stoppages, and makes the operation 150

of the device possible with practically any kind of wax so long as it is in a fairly fluid condition and with all the present day normally fluid waxes, whether they flow freely or slowly.

5 Having thus described my invention, what I claim and desire to protect by Letters Patent of the United States is:

1. In a floor waxing and polishing machine, the combination of a housing, two floor finishing 10 brushes mounted therein to rotate on parallel vertical axes, an electric motor mounted in said housing, and gearing between said motor and said brushes to rotate said brushes in opposite directions, and a waxing unit secured to the front of 15 said housing and freely movable vertically independently of said housing and operable to discharge wax in advance of said brushes at a point equidistant from the axes of said brushes, said unit comprising a reservoir for wax, a carriage 20 supporting said reservoir and having freely rotatable means mounted to roll on the floor and supporting substantially the entire weight of said unit and its contents directly on said floor, a pump mounted in said carriage for discharging the contents of said reservoir to the floor and 25 driving connections between said rotatable means and said pump to operate said pump by said rotatable means as said machine is manually slid back and forth over the surface of the 30 floor.

2. In a floor waxing and polishing machine, the combination of a housing, two floor finishing 35 brushes mounted therein to rotate on parallel vertical axes disposed in a plane at right angles to the direction in which said machine is normally moved back and forth over the floor, an electric motor mounted in said housing, and gearing between said motor and said brushes to rotate said brushes in opposite direction, and 40 a waxing unit detachably secured to the front of said housing and freely movable vertically independently of said housing and operable to discharge wax in advance of said brushes at a point equidistant from the axes of said brushes, 45 said unit comprising a reservoir for wax, a carriage supporting said reservoir and having freely rotatable means mounted to roll on the floor and supporting substantially the entire weight of said unit and its contents directly on said floor, a pump mounted in said carriage for discharging 50 the contents of said reservoir to the floor and driving connections between said rotatable means and said pump to operate said pump by said rotatable means as said machine is manually slid 55 back and forth over the surface of the floor.

3. In a floor waxing and polishing machine, the combination of a housing, two floor finishing 60 brushes mounted therein to rotate on parallel vertical axes, an electric motor mounted in said housing, and gearing between said motor and said brushes to rotate said brushes in opposite directions, and a waxing unit secured to the front of said housing and freely movable vertically independently of said housing and operable to discharge wax in advance of said 65 brushes at a point equidistant from the axes of said brushes, said unit comprising a reservoir for wax, a carriage supporting said reservoir and having freely rotatable means mounted to roll 70 on the floor and supporting substantially the entire weight of said unit and its contents directly on said floor, a pump mounted in said carriage for discharging the contents of said reservoir to the floor and driving connections between said 75 rotatable means and said pump to operate said

pump by said rotatable means as said machine is manually slid back and forth over the surface of the floor, the rotation of said rotatable means in one direction being operative to feed wax to the floor and in the other direction to stop the 80 delivery of wax to the floor.

4. The combination with a floor waxing and polishing machine comprising a housing, a floor polishing brush mounted to rotate in said housing in engagement with the floor, and an electric motor mounted in said housing and operatively connected to said brush to rotate the same, of a wax applying unit secured to the front of said housing and freely movable vertically with respect to said housing, said unit comprising a reservoir for wax, a carriage on which said reservoir is mounted and having freely rotatable means to roll on the floor and to support substantially the entire weight of said unit and its contents directly on the floor, a pump mounted in said carriage for pumping wax from said reservoir, a spout for delivering the pumped wax to the floor in advance of said brush and driving means between said rotatable means and said pump to operate said pump by said rotatable 100 means as said machine is manually slid back and forth over the surface of the floor whereby the amount of wax delivered to the floor is substantially proportional to the forward travel of said rotatable means over the floor.

5. The combination with a floor waxing and polishing machine comprising a housing, a floor polishing brush mounted to rotate in said housing in engagement with the floor, and an electric motor mounted in said housing and operatively connected to said brush to rotate the same, of a wax applying unit frictionally secured to the front of said housing and readily removable therefrom, and freely movable vertically with respect to said housing, said unit comprising a reservoir for wax, a carriage on which said reservoir is mounted and having freely rotatable means to roll on the floor and to support the weight of said unit and its contents on the floor, a pump mounted in said carriage for pumping wax from said reservoir, a spout for delivering the pumped wax to the floor in advance of said brush and driving means between said rotatable means and said pump to operate said pump by said rotatable means as said machine is manually slid back and forth over the surface of the floor whereby the amount of wax delivered to the floor is substantially proportional to the forward travel of said rotatable means over the floor.

6. The combination with an electrically driven floor polishing machine, including the casing therefor, of a wax applying unit comprising a carriage having wheels, a wax reservoir mounted on said carriage, a pump mounted on said carriage and operated by said wheels to pump wax from said reservoir and discharge it onto the floor when said carriage is rolled forwardly on its said wheels, and means to removably attach said unit to the front of said casing with said wheels resting on the floor and supporting substantially the entire weight of said wax applying unit and the contents of said reservoir, said means for securing said waxing unit to said casing affording relative movement between said casing and said unit in a relatively vertical plane only, whereby pressure of the wheels on the floor is substantially unaffected by the ordinary elevations and depressions of the floor.
